UNITED STATES PATENT OFFICE.

ALBERT F. ROCKWELL, OF BRISTOL, CONNECTICUT, ASSIGNOR TO THE NEW DEPARTMENT MANUFACTURING COMPANY, OF BRISTOL, CONNECTICUT, A CORPORATION OF CONNECTICUT.

HOPPER.

1,173,308.

Specification of Letters Patent.

Patented Feb. 29, 1916.

Application filed October 2, 1911. Serial No. 652,408.

To all whom it may concern:

Be it known that I, ALBERT F. ROCKWELL, a citizen of the United States, residing at Bristol, county of Hartford, State of Connecticut, have invented a certain new and useful Hopper, of which the following is a full, clear, and exact description, such as will enable others skilled in the art to which it appertains to make and use the same, reference being had to the accompanying drawings, forming part of this specification.

My invention relates to hoppers, and is particularly applicable to hoppers employed in feeding spherical articles, such as balls for ball bearings, which, while being manufactured, are automatically fed to grinding or sorting machines and the like.

Customarily, receptacles of this sort have an opening at the bottom for the outlet of the balls, and the balls in approaching or passing through such outlet sometimes become wedged and clogged, so that they do not feed freely through the same.

One object of my invention is to provide a hopper so constructed that the articles therein contained may be readily fed therefrom.

A further object is to provide a feeding receptacle having feeding means of such character that the articles acted upon cannot become clogged in the receptacle.

To these ends and also to improve generally upon devices of the character indicated, my invention consists in the various matters hereinafter described and claimed.

In the accompanying drawings Figure 1 is a plan view, partially broken away, of a hopper embodying my invention; and Fig. 2 is an elevation, chiefly in cross-section, 40 partially broken away.

In the illustrated embodiment of my invention —1— indicates the side walls of the receptacle or hopper adapted to receive articles, such as balls, which I prefer to put in motion in such a manner as to cause them to be fed freely to the outlet of my hopper.

Near the base of the receptacle, the sides, as at —2—, flare outwardly, and are preferably secured to a supporting base —3—, 50 as by being bolted thereto. Revolvably mounted on the base —3— is a conical-shaped bottom —4—, as preferably constructed, on which a mass of balls is adapted to rest. A convenient and preferable means 55 of supporting and driving this conical bot-

tom is by fastening the same upon a revoluble support, such as the spindle —5—. Preferably, this spindle —5— is adjustable longitudinally, so that the conical bottom —4— may be arranged at any desired distance from the flared sides —2— of my receptacle, whereby the width of the passage or channel, as at —8—, between these flared sides and the conical bottom, may be varied to accommodate balls of any desired size. 60 At times it is desirable to arrange the width of the passage, as at —8—, to accommodate two separate rows of balls, although customarily it is adjusted to receive a single row. The channel 8 here shown has the advantage 70 that by it the articles are spread out in a row (or rows) upon the bottom in position to be fed one-at-a-time therefrom.

As the bottom —4— revolves, the balls adjacent to it revolve, as does also a considerable portion of the mass of balls in the receptacle. The balls, as they revolve, work toward the periphery of the moving inclined bottom, and the bottom row as it revolves is fed into the outlet —9—. As the balls or other articles reach this outlet they are consecutively delivered thereto in a regular and orderly manner without jamming or clogging. This feeding of the balls continues as long as the conical bottom —4— revolves. 85

The outlet, as 9, is here shown as provided in the side wall 3^a of the base 3, extending away from the movable bottom 4 approximately at a tangent thereto, and having, as is preferable, a diameter sufficiently short 90 to maintain a single-file arrangement of the articles. In the illustrated device such single-file arrangement may be first brought about by the channel 8. In order that the outlet may have the various desired diameters, corresponding, for example, to the approximate diameters of the articles of the various batches operated upon, a series of detachable and interchangeable blocks, as 15, may be provided each with an outlet 9 of a certain diameter different from that of the others, such a block forming a portion of the wall 3^a. As here illustrated, a block, as 15, is shown as roughly sectoral in shape and held in assembled relation with the wall 3^a 100 by the tie-bands 16.

The longitudinal adjustment of the spindle —5— and thereby the conical bottom —4—, whereby the width of the passage as at —8— is varied, is preferably as follows: 110

The spindle — 5 — is shouldered as at — 10 — and thereby rests on and is moved with the inner member of a longitudinal, movable bearing — 11 —. The outer member of said bearing — 11 — preferably rests on a plate — 12 — positively secured, as by screws — 13 —, to the lower end of a sleeve — 7 —, which is threaded to the base as at — 14 — and thereby when the sleeve — 7 — is turned 10 is longitudinally movable with respect to the base. The upper bearing — 6 — is adapted to move longitudinally with and to guide the spindle, and to thus hold the conical bottom in place as it revolves.

15 The inner member of both the bearings — 6 — and — 11 — revolve with the spindle, and the revolving of the spindle and thereby the conical bottom — 4 — may be accomplished in any convenient manner, preferably by means engaging the lower end of 20 the spindle — 5 —, such as a system of pulley and belting not shown in the drawings.

I thus provide a device which is simple in structure and operation, and which positively and accurately feeds or delivers the articles being acted upon.

It will be understood that, although I have more particularly described a receptacle having a conical flare and a conical bottom as this is a preferable form since with it gravity aids in carrying the articles to the periphery of the bottom, the flare and the cooperating bottom need not necessarily be conical or inclined as the centrifugal force generated by the rotation of the bottom and the tendency of the articles to move toward the portions of the base having the greatest linear speed may be utilized alone to move the articles into and through the passages, as 8.

Having thus described my invention, what I claim as new and desire to secure by Letters Patent is —

1. In a feeding hopper for individually feeding the elements of a batch of like-diametered articles, in combination, a receptacle having sides forming a flare, and a traveling bottom adjacent, co-operating with and arranged at a distance from said flare to provide a passage, there being an outlet adjacent said bottom of a diameter having a length less than twice the diameter of the articles to be fed thereby to maintain a single file arrangement of said articles; substantially as described.

2. In a feeding hopper for individually feeding the elements of a batch of like-diametered articles, in combination, a receptacle having flaring walls, a rotatable bottom adjacent, co-operating with and spaced from the flare to provide a passage, and a wall for closing said passage, there being an outlet in said wall from said passage and adjacent the periphery of said bottom in a line substantially at a tangent

thereto and of a diameter having a length less than twice the diameter of the articles to be fed thereby to maintain a single file arrangement of said articles; substantially as described.

3. In a feeding hopper for individually feeding the elements of a batch of like-diametered articles, in combination, a receptacle having sides forming a conical flare, and an inclined traveling bottom projecting into said flare and arranged at a distance from said sides to provide a passage, there being an outlet adjacent said bottom of a diameter having a length less than twice the diameter of the articles to be fed thereby to maintain a single file arrangement of said articles; substantially as described.

4. In a feeding hopper for individually feeding the elements of a batch of like-diametered articles, in combination, a receptacle having flaring walls, a rotatable conical bottom projecting within the flare and spaced from said walls to provide a passage and a wall for closing said passage, there being an outlet in said wall from said passage and adjacent the periphery of said bottom in a line substantially at a tangent thereto and having a diameter of a length less than twice the diameter of the articles to be fed thereby to maintain a single file arrangement of said articles; substantially as described.

5. In a feeding hopper for individually feeding the elements of a batch of like-diametered articles, in combination, a receptacle having flaring walls with substantially smooth surfaces, a rotatable conical bottom having substantially smooth surfaces and projecting within the flare and spaced from said walls to provide a passage having substantially smooth walls, and a wall for closing said passage, there being an outlet in said wall from said passage and adjacent the periphery of said bottom in a line substantially at a tangent thereto and of a diameter having a length less than twice the diameter of the articles to be fed thereby to maintain a single file arrangement of said articles; substantially as described.

6. In a feeding hopper for balls and the like, in combination, a receptacle having substantially smooth sides forming a conical flare and an inclined traveling bottom having a substantially smooth surface and projecting into said flare and arranged at a distance from said sides to provide a channel having substantially smooth sides, there being an outlet adjacent said bottom; substantially as described.

7. In a device of the character indicated, a receptacle having flaring walls, a rotatable bottom adjacent, co-operating with and spaced from said walls to provide a passage, to a wall closing said passage, there being an outlet in said wall from said passage, and

means whereby elements presenting various sized outlets may be substituted for said outlet; substantially as described.

8. In a device of the character indicated, 5 a receptacle having flaring walls, a rotatable bottom adjacent, coöperating with and spaced from said walls to provide a passage, a wall closing said passage, there being an outlet in said wall from said passage, means 10 for varying the size of said passage, and means whereby elements presenting various sized outlets corresponding in size to the various sizes of said passage may be substituted for said outlet; substantially as described.

9. In a hopper, a receptacle having flaring walls, a rotatable bottom adjacent, coöperating with and spaced from said walls to provide an article passage, and a wall for 20 closing said passage, such wall including a removable block provided with an outlet communicating with said passage; substantially as described.

10. In a device of the character indicated, 25 a receptacle having flaring walls, a rotatable conical bottom projecting within said flare and spaced from said walls to provide a passage having parallel sides, a wall for closing said passage, and means for varying the 30 width of said passage; substantially as described.

11. In a device of the character indicated, 35 a receptacle having flaring walls, a rotatable conical bottom projecting within said flare and spaced from said walls to provide a passage having parallel sides, a wall closing said passage, there being an outlet in said wall from said passage, and means for varying the size of said outlet; substantially as 40 described.

12. In a device of the character indicated, 45 a receptacle having flaring walls, a rotatable

conical bottom projecting within said flare and spaced from said walls to provide a passage, a wall closing said passage, there 45 being an outlet in said wall from said passage, means for varying the size of said passage, and means whereby various sized outlets corresponding in size to the various sizes of said passage may be substituted for said 50 outlet; substantially as described.

13. In a hopper, a receptacle having flaring walls, a rotatable bottom projecting within said flare and spaced from said walls to provide an article passage, and a wall for 55 closing said passage, such wall including a removable block provided with an outlet communicating with said passage; substantially as described.

14. In a hopper, a base having a shaft 60 aperture, a receptacle having sides and carried by said base, an axially adjustable rotatable bottom for said receptacle arranged at a distance from said sides to provide an article passage said passage being adjustable 65 as to width by virtue of said axial adjustment, and means for effecting the rotatable support and axial adjustment of said bottom, such means comprising a shaft passing through said aperture and carrying said bottom and means for axially moving said shaft and for supporting the same comprising a sleeve adjustably mounted in said aperture and a bearing for said shaft supported by said sleeve and operatively connected with 70 said shaft to support the same; substantially as described.

In testimony whereof, I hereunto affix my signature, in the presence of two witnesses.

ALBERT F. ROCKWELL.

M. B. THORPE.

It is hereby certified that in Letters Patent No. 1,173,308, granted February 29, 1916, upon the application of Albert F. Rockwell, of Bristol, Connecticut, for an improvement in "Hoppers," an error appears in the printed specification requiring correction as follows: Page 2, line 39, for the word "passages" read *passage*; and that the said Letters Patent should be read with this correction therein that the same may conform to the record of the case in the Patent Office.

Signed and sealed this 1st day of August, A. D., 1916.
